UNITED STATES PATENT OFFICE.

ROBERT M. NICHOLS, OF SAN FRANCISCO, CALIFORNIA, ASSIGNOR OF ONE-HALF TO
CHARLES F. WAGNER, OF SAN FRANCISCO, CALIFORNIA.

BOTTLE-WRAPPING MACHINE.

1,245,932.

Specification of Letters Patent.

Patented Nov. 6, 1917.

Application filed January 25, 1917. Serial No. 144,763.

To all whom it may concern:

Be it known that I, ROBERT M. NICHOLS, a citizen of the United States, residing in the city and county of San Francisco and State of California, have invented a new and useful Improvement in Bottle-Wrapping Machines, of which the following is a specification.

The present invention relates to improvements in bottle wrapping machines where in a pair of arcuate drapers operate in conjunction with bottle feeding and paper wrapper feeding mechanisms to rotate the bottle and wrap the paper wrapper thereon 15 and also the means for twisting one end of the wrapper around the neck of the bottle; and the objects of my invention are—

First, to provide an improved bottle wrapping machine;

Second, to provide an improved bottle wrapping machine adapted to wrap a comparatively thin tissue paper wrapper around bottles;

Third, to provide improved means for twisting a comparatively thin paper wrapper around the neck of the bottle;

Fourth, to provide improved means for folding the paper wrapper around and into the hollow bottom of the bottle thereby effectively securing the wrapper to the bottle without the use of adhesives or other securing means; and

Fifth, to provide improved means for wrapping the exposed ends of the paper wrapper closely to the bottle.

I accomplish these several objects by means of the preferred form of the device disclosed in the drawings forming a part of the present specification, wherein like characters of reference are used to designate similar parts throughout the said specification and drawings, and in which—

Figure 1 is a broken vertical sectional view of the machine disclosing, in dotted lines, the location of the bottle and paper wrapper;

Fig. 2 is a transverse sectional view disclosing one inner end of the machine, the bottle and paper feeding mechanism, the 50 bottle releasing mechanisms and the arcuate drapers inclosing and wrapping a bottle;

Fig. 3 is a similar view disclosing one of the arcuate drapers extended to the bottle feeding mechanism and the manner in which 55 the bottle releasing mechanism is simultane-

ously operated to deliver a single bottle to the drapers;

Fig. 4 is a broken transverse section of the opposite inner end of the machine and the rotating yielding members for twisting 60 one end of the wrapper onto or around the neck of the bottle;

Fig. 5 is a sectional view taken on line 5—5 of Fig. 4 in the direction indicated by the arrows, disclosing the rotating yielding 65 members in normal position;

Fig. 6 is a view similar to Fig. 5 but disclosing the members in an operating position;

Fig. 7 is an elevation of the discharge end 70 of the machine;

Fig. 8 is an enlarged horizontal sectional view taken on line 8—8 of Fig. 1 of the drawings in the direction indicated by the arrows, disclosing the normal position of 75 the means for folding the end of the wrapper around and into the hollow bottom of the bottle;

Fig. 9 is a view similar to Fig. 8 but disclosing the folding parts in an operative 80 position;

Fig. 10 is a view of the opposite end of the machine to that shown in Fig. 7;

Fig. 11 is a view similar to Fig. 8 disclosing a portion of the wrapped bottle and the 85 means for twisting or closing the twisted end of the wrapper over the head of the bottle;

Fig. 12 is a similar view disclosing the same means ejecting the wrapped bottle 90 through the machine;

Fig. 13 is an enlarged sectional view taken on line 13—13 of Fig. 1 in the direction indicated by the arrows and disclosing the ejecting rod channeled to receive the cables 95 which operate it;

Fig. 14 is an elevation of a wrapped bottle disclosing the exposed end of the wrapper formed helical to the axis of the bottle whereby said end may be more firmly 100 secured to the side of the bottle;

Fig. 15 is a detailed view of the driving mechanism for the arcuate drapers.

Referring to the drawings the numeral 1 is used to designate a suitable housing or 105 frame in the lower portion of which is rotatably mounted a drive shaft 2 having a suitable driving sheave 3 secured to one end thereof and a gear 4 meshing with a gear 6 on a counter-shaft 7. The shaft 2 is also pro- 110

vided with a suitable sprocket 9. A second countershaft 11 is also provided with a sprocket 12 driven from the sprocket 9 by means of a chain 14.

5 The counter shaft 11 is also provided with a gear 16 which meshes with and drives pinions 17 and 18 of the stationary and movable arcuate drapers 19 and 20, respectively, as disclosed in Fig. 15 of the drawings.

10 The drapers 19 and 20 are composed of lower driving rollers 21 and 22 somewhat larger in diameter than the pinions 17 and 18, the purpose of which will hereinafter be more fully described, and supporting rollers 23 connected by means of connecting links 24. The drapers 19 and 20 are mounted upon the driving rollers 21 and 22 mounted within suitable stationary bearings 26 while the upper roller 23 of the stationary 20 draper 19 is rotatably mounted within suitable bearings 27 secured to the frame 1.

The movable draper 20 has its upper roller 23 rotatably mounted within the upper ends of a pair of arms 28 secured to a counter-shaft 29 having a pair of levers 31 carrying a roller 32 to engage a cam 8 on the counter-shaft 7.

A bracket 36 carries a slide or bottle feeding device 37 down which bottles 38 slide or roll by gravity. The feeding of the bottles 38 into the extended draper 20, as disclosed in Fig. 3 of the drawings, is controlled by means of a releasing cam 39 having a connection 41 to a lever 42 having a roller 43 arranged to be depressed by the lowering of the arm 28 to operate the releasing cam 39 and thereby release one bottle only to the extended draper 20.

A roll of wrapping paper 44 is rotatably 40 mounted upon suitable brackets 45 on the frame 1 and the web of paper passes over feeding rollers 46 through upper guides 47, guide rollers 48 and stationary guides 49 and between the upper rollers 23 of both stationary and movable arcuate drapers 19 and 20 which rotate the bottle 38 and thereby feed said web between the said arcuate drapers 19 and 20 and the bottle 38 thereby wrapping the paper around the said bottle 38.

50 Both of the feed rollers 46 are slightly elastic in order to more effectively engage and feed the web of paper and either one of the rollers 46 is provided with a cutting knife 51 arranged at an angle to the axes of said rollers 46 whereby the ends of each severed sheet of paper delivered to the arcuate drapers will lie at an angle to the sides of the web and thereby wind or wrap the loose end of the paper around the bottle in 60 the form of a helix thereby causing the paper wrapper to conform more closely to the body of the bottle 38.

The rollers 46 being slightly elastic and one roller very slightly smaller than the other it is evident that the knife 51 will be

slightly impressed into the opposite roller and at a different point on the periphery thereof at each rotation so as not to disintegrate said opposite roller 46 as would be the case were the knife 51 to always cut in 70 the same place.

The rollers 46 are geared together by means of gears 52 and are driven by means of an upper sprocket 53 rigidly secured to one of the rollers 46 and to a sprocket 54, 75 loosely mounted upon the cam shaft 11, by means of a chain 56. The sprocket 54 is provided with a clutch member 57 adapted to be engaged by a second clutch member 58 feathered to the counter shaft 11 and 80 operated by means of a lever 59 in turn actuated by a cam 61 on the shaft 2.

The shaft 2 is further provided with a sprocket 63 having a chain connection 64 to a sprocket 66 on a counter shaft 67 which 85 is also provided with a gear 68 meshing with a gear 69 of a rotating head 71 having teeth 72 which mesh with pinions 73 secured to yielding members 74 pivotally mounted by means of the arms 75 onto a sleeve 76 secured to the frame 1 and around which sleeve the rotating head is rotatably mounted.

A second sleeve 77 has slidably mounted thereon a cone 78 actuated by a lever 79 in 95 turn moved at the proper time by a cam 81 on the drive shaft 2 to move the said cone 78 inward against the rollers 82 of the arms 83. The arms 83 operate against the extensions 84 of the yielding members 74 to move 100 said members onto the paper cylinder formed by the wrapping of the paper web around the bottle 38 as disclosed in Fig. 5 of the drawings, and the continued rotation of the bottle 38, caused by the drapers 19 105 and 20, together with the pressure of the yielding members 74, twists the paper wrapper around the neck of the bottle, as disclosed in Fig. 6 of the drawings.

This leaves a small projecting cylinder of 110 paper wrapper extending beyond the head of the bottle and this cylinder is laid or twisted down onto the head of said bottle by means of the cup 86 attached to the end of a rod 87 having upper and lower 115 grooves 88 and 89 for the reception of operating and returning cables 91 and 92.

The operating cable 91 is secured to the outer end of the rod 87 and after passing through the lower groove 89 passes over a 120 roller 93 and onto a drum 94 loosely mounted upon the counter shaft 67. The drum 94 has a clutch member 95 adapted to be engaged by a similar clutch member 96 actuated by a lever 97 which is in turn operated by the face cam 98.

The cup 86 is operated by the sleeve 77 which is in turn operated by a lever or arm 101 operating against the face cam 102 on the drive shaft 2.

The other end of the paper wrapper after being formed or wrapped around the bottle 38 is turned or folded into the hollow bottom of said bottle 38 by means of the mechanism disclosed in Figs. 8 and 9 of the drawings, which consists of a pair of levers 103 pivotally mounted upon suitable brackets 104 secured to the frame 1 and connected by suitable connecting rods 106 to a lever 107 fulcrumed to the frame 1 and having the lower end thereof operated by the face cam 108 on the cam 61 for operating the paper feeding mechanism.

The levers are normally positioned as disclosed in Fig. 8 of the drawings. The cam 108 will, at the proper moment, move the levers 103 from the position shown in Fig. 8 to the position disclosed in Fig. 9 of the drawings, and fold the end 117 of the now cylinder paper wrapper over and into the hollow end of the bottle 38 as disclosed in Fig. 9 of the drawings. In order to move the edge of the end 117 of the cylindrical wrapper directly toward the axis of the bottle 38, I have provided what may be termed an auxiliary lever 109 pivotally mounted upon each lever 103 and normally held adjacent thereto by means of a T-shaped spring 111 resting on the back of each lever 103 and having the T-end thereof resting upon the auxiliary levers 109 as disclosed in Figs. 8 and 9.

By means of this arrangement I have provided a lever practically parallel to the edge 35 of the paper wrapper to be turned or folded and as this paper is generally of the tissue paper variety it must be delicately manipulated to prevent destruction.

When the levers 103 and 109 have moved 40 through a right angle from the position shown in Fig. 8 of the drawings, the paper wrapper will only lie at right angles to the sides or parallel to the bottom of the bottle 38 but in order to fold the paper into 45 the hollow bottom, the levers 109 must remain in the position shown while the levers 103 move up into said hollow bottom.

This is permitted by the T-shaped springs 111. When the levers 103 are returning to 50 normal position the slot 112 engages the pin 113 in the end of each lever 103 and thereby returns said levers 109 to normal position with a straight edge lying parallel to the side of the paper to be turned or folded into 55 the hollow bottom of the bottle 38.

A suitable delivery slide 121 serves to deliver or convey the wrapped bottles from the machine.

The operation is as follows: 60 The first step in the cycle is the rotation of the counter shaft 7 by means of the drive shaft 2 and the gears 4 and 6 which will cause the arms or levers 28 to extend the movable arcuate draper 20 to the end of the bottle feeding device or slide 37. The arms

28 will operate the releasing mechanism consisting of the roller 43 on the lever 42 and the connection 41 to the releasing cam 39 which will release the first bottle 38 only by moving from the position disclosed in Fig. 2 to the position disclosed in Fig. 3 of the drawings, permitting the passage of said bottle 38 down the slide 37 and extended draper 20 and into the arcuate stationary draper 19.

The upper ends of the axis of the roller 23 of the movable arcuate draper 20 are extended so as to rest within books 131 on the lower end of the slide 37 thereby effectively aligning and supporting the movable draper 20 when in an extended position.

The continued rotation of the cam will permit the spring 132 to restore the draper 20 to its normal or arcuate position thereby operating in conjunction with the stationary 85 arcuate draper 19 to inclose and rotate the bottle 38.

The cam 61 will next operate the lever 59 and connect the clutch 58 feathered to the rotating countershaft 11, which is rotating 90 both drapers 19 and 20 and the bottle 38 inclosed therein, to the clutch 57 of the sprocket 56 and thereby operate the paper wrapper feeding mechanism and feed a sheet of wrapping paper into the guides 47 guide 95 rollers 48 and lower guides 49 and then in between the top rollers 23 of both arcuate drapers 19 and 20.

The rotation of the bottle 38 and the drapers 19 and 20 will engage the end of the 100 paper wrapper and cause the same to be wrapped or wound around the bottle 38 in a substantially cylindrical form as disclosed in dotted lines in Fig. 1 of the drawings.

As soon as sufficient paper has been fed 105 to the drapers 19 and 20 to properly wrap the bottle 38 the cam 61 releases the paper feeding mechanism, the paper having been cut to the proper length and shape by the knife 51 as hereinbefore described.

The cam 81 now operates the lever 79 which in turn actuates the cone 78 to engage the extensions of the rotating yielding members 74 and move said members against the end of the cylindrical paper wrapper 115 adjacent the neck of the bottle 38 as disclosed in Fig. 6 of the drawings.

The rotation of the bottle 38 which is continuous as long as both drapers 19 and 20 inclose it, operating in conjunction with 120 the yielding members 74 will cause that end of the paper cylinder to become twisted around the neck of the bottle 38 as disclosed in Figs. 6, 11 and 14 of the drawings, leaving a smaller cylindrical paper extension of 125 approximately the diameter of the head of the bottle 38 extending beyond said head.

This extended cylindrical paper portion is next twisted onto the head of the bottle 38 by a forward movement of the cup 86 130.

said forward movement being caused by the face 102 of the cam 81 which moves the lever 101 operating the sleeve 77 which moves the cup 86 forward.

- 6 Meanwhile the face 108 of the cam 61 operates the lever 107 and causes the connections 106 to move the levers 103 and 109 to the position disclosed in Fig. 9 of the drawings thereby folding the opposite end 10 117 of the cylindrical paper wrapper over and into the hollow bottom of the bottle 38 thus effectively securing the wrapper to the said bottle.

The face 98 of the cam 81 next operates 15 the lever 97 to move the feathered clutch 96 into engagement with the clutch 95 of the drum 94 thereby winding the cable 91 onto said drum and moving the rod 87 and cup 86 against the head of the bottle 38 thereby 20 pushing the said bottle through the arcuate drapers 19 and 20, which have been meanwhile slightly released by the cam 8, and into the delivery slide 121. The drive rollers 21 and 22 are of a larger diameter than the 25 pinions 17 and 18 respectively, so that when the bottle 38 is moved longitudinally from the machine, the said larger diameter of the rollers 21 and 22 will hold the bottle above the teeth of the pinions 17 and 18 to prevent 30 said teeth from tearing the paper wrapper on the bottle 38 as said bottle is moved longitudinally into the delivery chute 121.

The above operation is repeated for successive bottles.

35 It is obvious from the foregoing that I have provided improved means for wrapping bottles with delicate or flimsy paper wrappers in such a manner that the said wrappers will closely conform to said bottles without the use of adhesives or other securing means.

The details of construction are so susceptible to variation that I do not wish to confine myself to the precise construction shown 45 herein but rather to avail myself of any modification that may fall properly within the scope of my invention.

Having thus described my invention what I claim as new and desire to secure by Letters Patent is—

1. A bottle wrapping machine comprising a pair of substantially arcuate drapers to rotate a bottle; a bottle feeding mechanism to feed a bottle at regular intervals to 55 the drapers; means for connecting one of the drapers with and operating the bottle feeding mechanism; a paper feeding mechanism to feed paper between the drapers and the bottle whereby said paper may be wrapped around said bottle; means for cutting the ends of the paper wrapper at an angle to the sides thereof whereby said ends may form a helix when wrapped around the bottle; means for twisting one 60 end of the wrapper around the neck of the 65

bottle; and means for folding the other end of the wrapper around and into the bottom of the bottle whereby said wrapper may be substantially secured to said bottle.

2. A bottle wrapping machine comprising 70 a pair of substantially arcuate drapers to rotate a bottle; a bottle feeding mechanism to feed a bottle at regular intervals to the drapers; means for connecting one of the drapers with and operating the bottle feeding mechanism; a paper feeding mechanism to feed paper between the drapers and the bottle whereby said paper may be wrapped around said bottle; means for cutting the 75 ends of the paper wrapper at an angle to the sides thereof whereby said ends may form a helix when wrapped around the bottle; means for twisting one end of the wrapper around the neck of the bottle; means for folding the other end of the 80 wrapper around and into the bottom of the bottle whereby said wrapper may be substantially secured to said bottle; and means for removing the wrapped bottle from the drapers and the machine. 90

3. A bottle wrapping machine comprising 95 a pair of substantially arcuate drapers arranged to engage and rotate a bottle; a bottle feeding mechanism; a bottle releasing mechanism arranged to release one bottle at a time; means for connecting one of the arcuate drapers with the bottle feeding mechanism and simultaneously operating the releasing mechanism to release a bottle onto said draper and to return said draper 100 to a substantially arcuate position; paper feeding mechanism to feed a paper wrapper between the arcuate drapers and the bottle whereby the said wrapper may be wrapped around the bottle by the rotation thereof; 105 means for cutting the ends of the wrapper at an angle to the sides whereby said ends may form a helix when wrapped around the bottle; means for twisting one end of the wrapper around the neck of the bottle; and means for folding the other end of the wrapper around and into the bottom of the bottle. 110

4. A bottle wrapping machine comprising 115 a pair of substantially arcuate drapers arranged to engage and rotate a bottle; a bottle feeding mechanism; a bottle releasing mechanism arranged to release one bottle at a time; means for connecting one of the arcuate drapers with the bottle feeding mechanism and simultaneously operating 120 the releasing mechanism to release a bottle onto said draper and to return said draper to a substantially arcuate position; paper feeding mechanism to feed a paper wrapper between the arcuate drapers and the bottle whereby the said wrapper may be wrapped around the bottle by the rotation thereof; 125 means for cutting the ends of the wrapper at an angle to the sides whereby said ends may form a helix when wrapped 130

around the bottle; means for twisting one end of the wrapper around the neck of the bottle; means for folding the other end of the wrapper around and into the bottom of the bottle; and means for ejecting the bottle from the arcuate drapers.

5. A bottle wrapping machine comprising a pair of substantially arcuate drapers to inclose and rotate a bottle; a bottle feeding mechanism; a bottle releasing mechanism on the bottle feeding mechanism; means for connecting one of the drapers to the bottle feeding mechanism and simultaneously operating the releasing mechanism whereby a 10 bottle may be delivered to the draper and for returning the draper to an arcuate position to inclose the bottle with both drapers; paper wrapper feeding mechanism arranged to cut the ends of the wrapper at 15 angles to the sides thereof and to deliver said wrapper between the bottle and drapers whereby said wrapper may be wrapped around the bottle by the rotation thereof with the ends of the wrapper forming a 20

helix relatively to the axis of the bottle; a 25 pair of rotating yielding members to engage one end of the wrapper and twist same around the neck of the bottle, said members conforming to the shape of said neck; and means for folding the other end of the wrap- 30 per around and into the bottom of the bottle.

6. The combination with a bottle wrapping machine of a bottle feeding mechanism; a pair of arcuate drapers arranged to inclose and rotate a bottle and to wrap a 35 paper wrapper around said bottle when said wrapper is fed between the drapers and the bottle; means for connecting one of the drapers to the bottle feeding mechanism to receive a bottle therefrom and to return said 40 draper to an arcuate position to inclose and rotate said bottle; and means for feeding a paper wrapper between the drapers and the bottle.

In witness whereof I hereunto set my sig- 45 nature.

ROBERT M. NICHOLS.
